CARL H. RICH, OF WORCESTER, MASSACHUSETTS, ASSIGNOR TO RILEY STOKER CORPORATION, OF WORCESTER, MASSACHUSETTS, A CORPORATION OF MASSACHUSETTS

TUYÈRE BLOCK

Application filed July 9, 1926. Serial No. 121,465.

This invention relates to tuyère blocks, and more particularly to tuyère blocks as used in connection with automatic stokers.

In certain types of automatic stokers, it is customary to arrange tuyère blocks to form a support for the fuel bed and supply air thereto, and they are subjected to extreme heat from the fire above. Such a tuyère block is usually of cast iron, and the excessive heat causes it to expand and grow, gradually becoming permanently enlarged. This heat is moreover applied mainly at the exposed end of the block. As a result, the tuyère block as heretofore constructed has been subjected to enormous internal strains caused by the uneven expansion. Cracks have appeared, causing fragments to drop off, thus exposing large air openings, and rendering the block useless as a support for the fuel. Such rapid deterioration in the past has been the cause of large expense and frequent shut downs of the furnace.

In stokers having blocks piled or arranged closely adjacent to each other, it is often found that there is not sufficient room for expansion between the blocks, so that they crowd each other at certain points and open up passages at other points, or otherwise cause improper action of the furnace. This defect is particularly noticeable in a stoker of the type in which two sets of tuyère blocks are mounted for relative reciprocatory movement on the side walls of adjacent retorts. As the growth takes place mainly at the exposed end of the block, this has forced the side walls apart, causing them to bind, and opening up large spaces through which siftings would fall.

It is accordingly the main object of my invention to overcome such difficulties and to provide a tuyère block construction which permits expansion under the influence of the extreme heat to which it is necessarily subjected without the setting up of detrimental internal strains and the consequent breakage or warpage of the block.

A further object of my invention is to provide, for underfeed stokers having relatively moving retort side walls, tuyère blocks which may be carried on the walls and will be free to increase in size laterally without forcing

the walls apart or otherwise seriously affecting the operation of the stoker.

A further object is to provide a tuyère block which will admit air efficiently to the fuel bed, and which will maintain this efficiency throughout a long life before requiring replacement. 55

With these and other objects in view as will be apparent to one skilled in the art, my invention resides in the combination of parts set forth in the specification and covered by the claims appended hereto. 60

According to my invention, I provide a tuyère block with a portion cut away at that part of the block which is subjected to the greatest heat, and which is so arranged that the block is free to expand into the cutaway portions without causing serious internal strains. One form of block, arranged to be piled in a steplike formation, may comprise 70 an approximately horizontal web portion, provided with a grooved surface and having slots cut through the web, thus permitting the block to expand inwardly or increase in size. The grooved surface may be so arranged as to form tuyère openings or air passages, and to direct the air in a desired manner into the fuel bed. In applying my improved tuyère block to stokers having relatively movable retort side walls, I may so 75 construct the blocks that they will slope away, at the ends exposed to the heat, from the dividing line between the retorts. In this way, a block is free to expand without crowding against the laterally adjacent block. 80 Also, if desired, space may be provided for expansion between the blocks in a single tier, as by sloping the bottom of a block at its nose portion to permit vertical growth of the noses of the blocks. 85 90

Referring to the drawings, in which like reference numerals indicate like parts:

Fig. 1 is a perspective view of one of my improved tuyère blocks, as constructed for a stoker having relatively moving retort side walls; 95

Fig. 2 is a bottom plan view on a reduced scale of the block shown in Fig. 1;

Fig. 3 is a top plan view of several of 100

these blocks assembled in their proper relative positions;

Fig. 4 is a side elevation of the blocks as arranged in Fig. 3;

Fig. 5 is a diagrammatical cross section showing tuyère blocks mounted on the retort side walls of an underfeed stoker; and

Fig. 6 illustrates diagrammatically an arrangement of tuyère blocks which have upwardly sloping bottoms.

The embodiment of my invention illustrated in the drawings comprises a tuyère block adapted for use on stokers of the type shown in the patent to Riley No. 1,322,822. In such a stoker, as shown in Fig. 5, two sets of tuyère blocks 1 and 2 may be mounted on the opposed side walls 3 and 4 of adjacent retorts of an underfeed stoker. These side walls are arranged to be reciprocated relative to each other by suitable mechanism. As shown in Fig. 3, the adjacent faces of the two sets of blocks are arranged close to each other for such reciprocal movement, and they are provided with tuyère passages 5 which communicate at their inner covered ends with the air trunk 6 beneath the blocks and between the side walls 3 and 4 of the retorts. The retort bottoms 7 are stationary, and the sifting of fine coal between them and the side walls is prevented by siftings strips 8. The blocks are superimposed on one another in a steplike formation, each having a nose exposed directly to radiant heat and a portion covered by the block above which is cooled by the air fed thereto, this arrangement being such as to produce radically different conditions at the opposite ends of each block which often result in uneven expansion of the different parts and a permanent growth of the exposed nose portion.

To overcome this difficulty, I provide a block which may grow permanently without detrimental effect on either itself or the neighbouring blocks and so give a longer life of useful service. One form of block, as illustrated, may be constructed with a substantially horizontal web portion 10, which is preferably well rounded off on the outside corner of the nose where exposed to the heat. This is desirable in order to avoid the excessive burning of the block which would take place if a sharp corner projected into the fuel bed. Each tuyère block is preferably provided with a grooved surface to form tuyère openings and to hold ashes thereon, as well as to aid in cooling the block. The grooved surface may be formed by means of ribs projecting from the central web portion. As shown, the upper face of the web 10 has four vertical ribs 11, 12, 14 and 16. On the lower surface of the web portion I have shown seven ribs 18 to 24 inclusive. These lower ribs are directed at various angles, as illustrated, so as to distribute the air from a central space 25 into the fuel bed. The ribs

on the upper surface preferably slope downwardly as they approach the edge of the web, so as to avoid sharp corners which would project upwardly into the fuel. Ribs 11 and 14 are made comparatively short so as to avoid interference with ribs 18 and 19 respectively on the superimposed block, when the parts are assembled as shown in Fig. 3. Ribs 12 and 16 are made comparatively long, and are so arranged as to extend between ribs 18 and 19, and 19 and 20 respectively on the superimposed block. A depending flange 26 is provided on the bottom and along the side of the block to form a continuation of rib 24, and thereby prevent the escape of air at this point. A slightly raised lug 27 (Fig. 3) projects laterally from the rib 12 and is so arranged as to fit against the side of the rib 18 on the superimposed block. The two ribs 18 of adjacent blocks fit in the space between the two lugs 27 on the lower blocks, whereby the blocks are properly positioned. Downwardly depending members 28 and 30 may be formed, as shown in Figs. 2 and 4, on the under surface of each block for the purpose of entering suitable openings in the supporting casting which forms a part of the retort side wall. A recess 32 may be provided for the head of a bolt to be used in fastening the block to the side wall, these parts 28, 30 and 32 being formed as desired and not constituting essential features of this invention.

As shown in Fig. 3, the blocks are so arranged that only the nose portion of each block is exposed to the intense heat from the fuel bed above. In order to provide room for permanent growth of the block and thus eliminate internal strains and the resulting cracks, I may form cutaway portions in the nose portion of the web 10. These cutaway portions preferably extend entirely through the web as slots 35 and 36 so as to give the blocks ample room and freedom for growth inwardly. These slots may be located between the upper ribs 11 and 12 and ribs 12 and 14. They preferably are so placed as to come directly over ribs 12 and 16 on the block beneath, thus to a certain extent preventing the escape of air upwardly through the slots. If desired, the slots may be filled with a refractory substance, such as a suitable clay, which will prevent the escape of air therethrough and yet be sufficiently yielding as to permit expansion of the metal.

It has been found in the past that grate blocks tend to expand laterally at that portion where I have shown ribs 11 and 18. This lateral expansion, which is more pronounced at the end of the block, has caused each block to crowd against the adjacent block on the other side wall, thus tending to force them apart and form large openings through which air might escape and siftings drop. In my improved tuyère block, I have been able to overcome this difficulty by sloping the side

walls 11 and 18 of the blocks away from each other at the portions exposed to the heat, thus forming a wedge shaped space 40 into which each block is free to expand without crowding the adjacent block. This space 40 does not permit siftings to drop through, as the opening is covered by the web of the block beneath, as shown in Fig. 3.

In Fig. 6 I have illustrated diagrammatically a modified form of my invention. Tuyère blocks 45 are arranged in steplike formation, and the bottom of each block is sloped upwardly, thus providing a space 46 into which the exposed nose of the block may

15 expand without crowding the block beneath.

It will be evident to those skilled in the art that I have provided a tuyère block in which the slots as shown entirely eliminate the formation of cracks and the breaking off of parts 20 of the block and the consequent exposure of large openings, because they provide spaces into which the block may grow freely when exposed to the excessive heat of a furnace as well as the severe physical and chemical conditions to which such blocks must be subjected.

When assembled as by bolting the blocks on a supporting side bar, the ribs on the superimposed blocks form long narrow tuyère passages running from the central 25 space 25 to the outer edges of the blocks. This space 25, as is understood, opens to the air chamber 6 beneath and between the retorts. The ribs serve not only to separate the webs 10 and form tuyères but to

30 strengthen the block and to provide radiating surfaces of large extent which transfer the heat from the block to the entering air, thus preheating the air and cooling the block. It will be apparent that the cutaway portions or slots may be variously located and made in suitable sizes and numbers to carry out the purposes of this invention, and that various types of tuyère and grate blocks used 35 in stokers may be constructed in accordance with my invention.

Having thus described my invention, what I claim as new and desire to secure by Letters Patent is:

1. An underfeed stoker having relatively 40 reciprocal side walls forming retorts, one wall of each retort being parallel and adjacent to the wall of an adjoining retort and independent sets of tuyère blocks mounted on said relatively movable walls, the laterally 45 adjacent tuyère blocks having their adjacent faces sloping away from each other throughout their heat exposed portions to provide a space into which said blocks may expand laterally without crowding.

2. An underfeed stoker comprising relatively reciprocal side walls forming retorts, one wall of each retort being parallel and adjacent to the wall of an adjoining retort, and a set of tuyère blocks mounted in

5 cable walls to support the fuel bed and admit air thereto, said tuyère blocks having substantially horizontal web portions and ribs on their upper and lower surfaces, and being so constructed as to slope away throughout their exposed portions from the dividing line between said adjacent relatively reciprocable walls so as to form spaces for the lateral expansion of said blocks.

3. A tuyère block for a stoker adapted to 70 be piled with other blocks in a step-like formation to support fuel thereon comprising an extensive plate, ribs thereon which project downwardly to form tuyère openings between said plate and the plate beneath, said ribs being spaced apart at their rear ends for the introduction of air to the tuyère openings, and ribs on the top of the plate which are to contact with the fuel bed, said plate having elongated slots between and substantially 75 parallel with two sets of ribs on opposite sides of the plate which extend inwardly from the edge of the plate for a sufficient distance to permit inward growth of the heat exposed portion thereof.

4. A stoker tuyère structure comprising 80 substantially horizontal plates piled in a step-like spaced relation to permit air to flow therebetween to the fuel bed, each plate having a slot extending inwardly from the edge to permit growth thereof, and means to obstruct the flow of air vertically through the slot of the adjacent superposed plate.

5. A stoker comprising a set of tuyère 85 blocks having plates grooved on their under sides which are piled in a step-like formation to permit air to flow therebetween, said plates having slots extending inwardly from their edges to permit growth thereof, the slots being located above projecting portions of the 90 plates below which prevent the escape of air vertically through the slots.

6. A tuyère block for a stoker comprising a 95 plate adapted to be piled in a step-like formation with other blocks, said plate having ribs on the upper side thereof, which serve to space the plate from the one above and form tuyères, and a slot extending vertically through the plate and inwardly from the normally heat exposed edge for a sufficient distance to permit 100 growth of the plate, one rib on the plate being shaped and located in such a position relative to the slot on a plate above as to underlie the same and prevent the passage of air therethrough.

7. A stoker comprising two sets of tuyère 105 blocks mounted side by side in a step-like formation to support fuel and introduce air thereto, each block having ribs providing air admitting grooves between the blocks, the unexposed portions of laterally adjacent blocks having contacting and substantially 110 parallel sides, and the sides of the portions exposed to direct heat radiation being beveled and sloping away from each other 115 120

125 130

at a slight angle to permit lateral growth throughout said exposed portions.

8. A stoker comprising a plurality of tuyère blocks mounted in step-like formation with their nose portions exposed to the heat and provided with grooves for admitting air to a fuel bed supported thereon, the adjacent faces of the blocks being in contact in the unexposed portions thereof and sloping away from each other throughout their heat exposed portions to permit growth under the influence of the heat without crowding.

9. A tuyère block for a stoker comprising a plate having a portion adapted to contact with a fuel bed and be exposed to the heat thereof, and a series of ribs integral with the plate and extending away from the heat exposed edge thereof, said ribs being spaced apart to provide channels for the flow of air to the fuel bed, said plate having an elongated slot which extends through the plate between two of the ribs and away from the heat exposed edge for a considerable distance to permit inward growth of the heat exposed portion, the ribs serving to strengthen the plate adjacent to the slot.

Signed at Worcester, Mass., this 7th day of July, 1926.
